US00D793429S

(12) **United States Design Patent** (10) Patent No.: **US D793,429 S**
(45) Date of Patent: **** Aug. 1, 2017**

(54) **DISPLAY SCREEN OR PORTION THEREOF WITH ICON**

(71) Applicant: **Samsung Electronics Co., Ltd.**, Gyeonggi-do (KR)

(72) Inventors: **Hangyul Kim**, Seoul (KR); **Sungmin Kim**, Seoul (KR); **Min-Hee Lee**, Seoul (KR); **Yunjae Lee**, Seoul (KR)

(73) Assignee: **SAMSUNG ELECTRONICS CO., LTD.**, Gyeonggi-Do (KR)

(**) Term: **15 Years**

(21) Appl. No.: **29/550,273**

(22) Filed: **Dec. 31, 2015**

(30) **Foreign Application Priority Data**

Aug. 11, 2015 (KR) 30-2015-0040531

(57) **CLAIM**

We claim, the ornamental design for a display screen or portion thereof with icon, as shown and described.

DESCRIPTION

The FIGURE is a front view of a display screen or portion thereof with icon showing our new designs.

The broken line showing of the display screen in the FIGURE is included for the purpose of illustrating environment structure and forms no part of the claimed design.

1 Claim, 1 Drawing Sheet
